UNITED STATES PATENT OFFICE.

HARRY WEARNE, OF RIXHEIM, GERMANY.

DESIGN FOR WALL-PAPER.

SPECIFICATION forming part of Design No. 31,992, dated December 12, 1899.

Application filed November 20, 1899. Serial No. 737,699. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, which represents a plan view of a strip of wall-paper embodying the features of my design.

The leading feature of the design consists in the representation of a latticed frame, a foreground of flowers, and a background which includes a vase and a base therefor.

The details of the design are as follows: A frame is presented constructed of filigree lattice-work combined with foliate columns and scrolls, a span in the shape of a chain of flowers being at the top of the frame, while

the bottom of the frame is represented as solid and provided with a pendent decoration. A bunch of flowers is apparently located at the bottom portion of the frame, and flowers also appear as decorating the upper portion of the frame, while floral sprays appear to drop from the top to the bottom of the frame. In the background a vase appears containing flowers and as supported on a base, the vase and a portion of the base being visible through the space surrounded by the frame.

Having thus described my invention, I claim as new and desire to secure by Letters Patent—

The design for wall-paper, as herein shown and described.

HARRY WEARNE.
